UNITED STATES PATENT OFFICE.

ERNEST WIRTH, OF SCHOPFHEIM, GERMANY, ASSIGNOR TO LOUIS GREINER, OF TOLEDO, OHIO.

BELT-SHIFTING MEANS.

No. 897,441.

Specification of Letters Patent.

Patented Sept. 1, 1908.

Application filed December 9, 1907. Serial No. 405,758.

To all whom it may concern:

Be it known that I, ERNEST WIRTH, a subject of Germany, and a resident of Schopfheim, I. W. Baden, Germany, have invented 5 a certain new and useful Belt-Shifting Means; and I do hereby declare the following to be a full, clear, and exact description of the invention, such as will enable others skilled in the art to which it appertains to make and 10 use the same, reference being had to the accompanying drawings, and to the figures of reference marked thereon, which form a part of this specification.

My invention relates to belt shifting apparatus, and has for its object the provision of a device of this class, which forms a strong and durable antifriction support for the belt when not on the drive-pulley, but which obviates the use on the shaft of the usual loose pulley, 20 and provides simple and efficient means for shifting the belt from the pulley to the support or vice versa.

The operation, construction, and arrangement of the parts of my invention are fully 25 described in the following specification and illustrated in the accompanying drawings, in which,—

Figure 1 is a side elevation of the device comprising my invention with an associated 30 drive-pulley and belt. Fig. 2 is a top plan view thereof, and Fig. 3 is a transverse section taken on the dotted line $z-z$ in Fig. 1.

Referring to the drawing, 1 designates a drive-shaft, 2 a drive-pulley carried thereby, 35 and 3 a belt operating on said pulley.

Suspended from the ceiling by hangers 4, 40 or otherwise suitably supported at one side of the pulley 2, is the curved bar or member 5, which commences in advance of the vertical center of the pulley in the plane of its top and thence follows the course of the belt for a portion of its distance around the pulley, as shown, so that the curved portion of the bar approximately conforms to a segment 45 of the pulley rim. Projecting laterally from the curved portion of the bar 5 toward the pulley rim with their free ends terminating in close proximity thereto are a plurality of spaced spindles 6 each of which carries a 50 roller or revoluble sleeve 7. These sleeves combine to form an antifriction segmental support upon which the belt is shifted when thrown from the pulley 2, thus performing the function of the usual loose pulley.

55 8 designates a bracket, which is carried at

the upper forward end of the bar 5, and in which the transverse shift-bar 9 is mounted for longitudinal reciprocatory movement. While the bracket 8 is shown as extending upwardly and laterally of the bar 5 toward the belt 3 with its free end terminating in a pendent lip, which lip and the supporting leg of the bracket are provided with registering slide-ways for the shaft-bar 9, any other form of bracket can be used if desired. The shift-bar 9 has its inner end, relative to the bar 5, extended over the belt 3 and provided with a pendent spindle 10 on which the revoluble sleeve 11 is mounted for contact with the contiguous edge of the belt when the shift-bar is moved to shift the belt from the pulley to the sleeves 7. The shift-bar 9 is normally retained at its limit of outward movement, as shown in Fig. 2, by the action thereon of the coiled contraction-spring 12, 60 which has one end attached to the bracket 8 and its other end attached to the end of the shift-bar opposed to the spindle 10. A shift cord or chain 13 is attached at one end to a finger 14 projecting from the inner or spindled 65 end of the shift-bar, thence extends longitudinally of the shift-bar over a sheave 15 carried by an arm 16, projecting from the bracket 8, and thence downward in position to be pulled by an attendant.

The mechanism employed for throwing the belt upon the pulley from the sleeves 7, consists of the rear shift-bar 17, which is carried by the bracket or arm 18 for longitudinal movement transversely of the bar 5. The bracket or arm 18 is carried by the curved portion of the bar 5 and is shown as being of similar construction to the bracket 8. Projecting laterally from the shift-bar 17 contiguous to the inner side of the supporting leg of the bracket 18 are one or more ears 19, which carry the spindles 20. These spindles project toward the shaft 1 and carry loose sleeves 21, which are intended to coact with the inner edge of the belt to throw it from the supporting-sleeves 7 upon the pulley when the bar 17 is shifted for such purpose. A coiled contraction-spring 22 connects the inner or pulley-end of the shift-bar 17 and the bracket 18 to normally maintain the former at its limit of outward movement with the spindles 20 in contiguous position to the bar 5, as shown in Fig. 2. The shifting of the bar 17 is manually effected by the pulling of the shift-cord or chain 23, which passes 70 75 80 85 90 95 100 105 110

- upward over a sheave 24, carried by an arm 25 projecting from the bracket 18, thence horizontally around a sheave 26 carried by the angled end 17^a of the shift-bar 17 and back to the bracket 18 with its end suitably fixed thereto, thus causing a pull on the cord or chain to effect a movement of the shift-bar in the direction of the pulley against the tension of its spring.
- 10 It is apparent from the above description that to throw the belt from the drive-pulley to the supporting spindles 6 it is only necessary to pull downward on the shift-cord or chain 13 to impart the requisite shifting movement to the shift-bar 9 against the tension of its spring; and to throw the belt from the spindles 6 to engagement with the pulley it is likewise only necessary to pull downward on the shift-cord or chain 23 to impart the requisite shifting movement to the shift-bar 17 against the tension of its spring.
- I wish it understood that I do not desire to be restricted to the particular arrangement and construction of the parts shown and described, as obvious modifications will occur to persons skilled in the art.
- Having thus described my invention, what I claim as new and desire to secure by Letters Patent, is,—
- 30 1. The combination with a pulley and the belt operating thereon, of a belt support at the side of the pulley, independent means movable laterally of the pulley for throwing the belt from the pulley to the support and vice versa, and means associated with each of said shifting means to yieldingly retain it in one position of its movement.
2. The combination with a pulley, of a belt support at the side thereof, and a set of belt-shifter members capable of relative longitudinal reciprocatory movements in planes transverse to the pulley, one member being

movable to shift a belt from the pulley to the support and the other being movable to shift a belt from the support to the pulley.

3. The combination with a pulley, of a stationary belt-support at the side thereof comprising a member laterally spaced from the pulley and having a portion curved to conform to a segment of the pulley, said member having spaced belt supporting portions projecting toward the pulley, and laterally spaced longitudinally reciprocatory means relatively movable to shift a belt on and off the pulley.

4. In association with a pulley, a belt support comprising a part laterally spaced from the pulley and having sleeved projections thereon extending toward the pulley-rim and terminating in proximity thereto, said projections being arranged in the form of a segment of the pulley rim to adapt them to support a belt when shifted thereon from the pulley, means carried by the support for shifting a belt thereto from the pulley, a shift-bar carried by the support for longitudinal movement laterally of the pulley, said bar having a lateral projection extending between the projections on said part in the path of shifting movement of the belt, means acting on the shift-bar to normally retain it with its projection in contiguous position to said part, and a pull-member associated with the shift-bar and adapted, when pulled, to effect a movement of the shift-bar from normal position to throw a belt from the support to the pulley.

In testimony whereof I have hereunto signed my name to this specification in the presence of two subscribing witnesses.

ERNEST WIRTH.
